[57] CLAIM

The ornamental design for a side chair, as shown and described.

DESCRIPTION

FIG. 1 is a perspective view of a side chair taken from above and from the right side showing my new design;

FIG. 2 is a rear elevational view thereof;

FIG. 3 is a left side elevational view thereof; the right side being a mirror image;

FIG. 4 is a front elevational view thereof; and,

FIG. 5 is a top plan view thereof.

FIGS. 3 through 5 have been showing on an enlarged scale with respect to FIGS. 1 and 2.
